UNITED STATES PATENT OFFICE.

GEORGES AUGUSTIN SALINS, OF VINCENNES, FRANCE, ASSIGNOR TO PATHÉ CINEMA,
ANCIENS ÉTABLISSEMENTS PATHÉ FRÈRES, OF VINCENNES, SEINE, FRANCE.

MACHINE FOR TREATING CINEMATOGRAPH FILMS.

Application filed August 20, 1920. Serial No. 404,764.

To all whom it may concern:

Be it known that I, GEORGES AUGUSTIN SALINS, citizen of the Republic of France, residing at 16 Rue Joseph Gaillard, Vincennes, Seine, in the Republic of France, have invented new and useful Improvements in Machines for Treating Cinematograph Films, of which the following is a specification.

10 This invention relates to an improved device for feeding the film in the machines used for developing, fixing, washing and otherwise treating cinematographic films made of any material, this device being 15 equally applicable to drying machines and other apparatus employed in treating cinematographic films.

In the accompanying drawing which is given by way of example:

20 Fig. 1 is a cross section on the line 1—1, Fig. 3 of a vat used in the improved device, certain parts being omitted, for the sake of clearness;

25 Fig. 2 is a similar cross section on the line 2—2, Fig. 3, certain parts being omitted;

Fig. 3 is a longitudinal section along the line 3—3, Fig. 1, the film being shown in part only;

30 Fig. 4 is a horizontal section along the line 4—4, Fig. 3, the film being removed;

Fig. 5 is a diagrammatic perspective view showing the arrangement of the shafts and supporting members, the reels or rollers 35 being not shown;

Fig. 6 is a diagrammatic plan view showing the movement of the film in two consecutive elements;

Fig. 7 is a detail plan view showing the 40 clutch driving device for the main shaft.

The apparatus for the developing, fixing, washing and the like of cinematograph films comprises a plurality of vats, such as 1 and 2 (Figs. 1 and 6), each being employed for 45 a single operation, although in some cases a number of vats may be required for a single operation, the washing for instance.

As shown in the drawing, four shafts 3, 4, 5, 6 grouped in diamond shape (Fig. 1) 50 are arranged in the upper part of each vat in the longitudinal direction of the latter; these shafts are rotatable in bearings 7 (Fig. 3) carried by a frame or cover 8. They are connected by small gear wheels

of pulleys such as 9 and belts 10, 11, so that the shafts 3, 4, 5 rotate in the same direction and the shaft 6 in the opposite direction.

At the lower part of each vat are disposed two shafts or spindles 12 and 13 which are in vertical alignment with the shafts 4 and 5, respectively. A rod 14 extends downwardly through the left hand part of the cover 8 and carries a transverse supporting rod 15 upon which the ends of the shafts 12 and 13 are pivoted. The rod 14 60 may slide in a sleeve 16 secured to the cover 8 and it may be adjusted at the desired height by the set screw 17; a like rod 18 carries a transverse supporting rod 19 upon which the opposite ends of the shafts 12, 13 65 are pivoted. Said rod 18 is adapted to slide in a sleeve or ring 20 secured at the right hand part of the cover 8; at the top of the rod 18 is secured an insulated contact member 21 (Fig. 5) which may engage fixed 70 contacts 22 provided in an alarm circuit which comprises the battery 23 and bell 24.

The shaft 3 has disposed thereon a toothed drum 25 (Figs. 1 and 3) whereby the film is caused to enter the receptacle; at the other end of the said shaft is disposed a roller 26 for guiding the film when leaving the receptacle.

The shafts 4, 5 are provided with rollers 27 disposed in alignment in the transverse direction and the shaft 6 carries similar rollers 28 which are all staggered by the length of half a roller (Fig. 4) with respect to the rollers 27. Said rollers 27, 28 are preferably mounted upon the shafts with a slight friction so that they rotate with the shafts and act to feed the film and can however slip upon the shafts if required. Similar rollers 29 in alignment with the rollers 27 are freely mounted on the lower shafts 95 12, 13. The shafts 4, 5, 6 may also be stationary in which case the rollers are freely mounted thereon, the pulleys 9 and belts 10, 11 being then omitted. The number of the rollers upon each shaft is normally 20, 100 but this number may be increased or reduced as desired.

In the example shown, the main shaft or upper shaft 3 is operated through the medium of bevel gears 30 (Fig. 4) by a shaft 31 carrying a large gear 32 and a smaller gear 33 respectively actuated by gears 34 and 35 freely mounted on a driving shaft

36. On the latter is splined a clutch sleeve 37 which may be brought into engagement either with the wheels 34 or 35 or held in the intermediate inoperative position as shown.

The movement of the film is effected as follows:

The film is entrained by the toothed drums 25 (Fig. 1) and passes—with the emulsion side down—over the first roller of the shaft 5, descends vertically upon the first roller of 13, ascends upon the first roller of 6, descends again upon the first roller of 12, ascends thence upon the first roller of 4, passes horizontally upon the second roller of 5 and so on. When leaving the last roller of 4 (Fig. 6), the film is guided by the roller 26 disposed opposite the toothed drum 25 of the following receptacle.

20 The progressive movement of the film takes place as shown in Fig. 6. When on the rollers of 6, the film can be reversed to prevent it from bearing upon the emulsion side.

In case only a single element is required, 25 the roller 26 is replaced by a toothed drum.

Regulation of the development (Fig. 5).

The time required for developing is reduced by stopping the shaft 3 by means of 30 the clutch 37, whereby the feed of the film to the vat is stopped. The film being still drawn out by the feeding drum of the next vat, the free ends of the shafts 12 and 13 connected to the cross shaft 38 will move 35 upwardly as shown in broken lines in Fig. 5, while the other ends will pivot about the cross shaft 15, thus raising the rod 18 and reducing the length of the path of the film through the liquid in the vat. Marks are 40 made upon said rod 18 to indicate the various periods of development. When the desired mark has been attained, the shaft 3 may be operated again and the lower shafts 12, 13 may be restored to the horizontal 45 position by unscrewing the set screw 17 and raising the rod 14 to the requisite height.

To increase the time of development, the shaft 3 is actuated through the gears 35 and 33 at a greater speed than the corresponding shaft of the following receptacle; the free end of each of the shafts 12 and 13 descends, and in order to bring the two shafts again into the horizontal position the 55 rod 14 is moved downwardly and held at the requisite depth by means of the set screw 17.

Should the film break, the lower shafts 12, 13 will pivot downwardly about the cross rod 15 under the weight of the film, the rod 18 will drop and the member 21 by contacting with the contact 22 will close the circuit of the bell 24 and at the same time prevent the lower rollers 29 from dropping 60 upon the bottom of the vat.

Having now described my invention what I claim as new and desire to secure by Letters Patent is:

1. A machine for treating cinematograph films comprising a treating vat, parallel upper shafts arranged in the upper part of said vat, in the longitudinal direction of the same, lower longitudinal shafts arranged in the lower part of the vat film supporting rollers placed end to end upon said shafts and means for feeding the film through the vat and around the rollers.

2. A machine for treating cinematograph films comprising a treating vat, three parallel upper shafts arranged in the upper part of said vat and in the longitudinal direction of the same, two of these shafts being in a horizontal plane and the third shaft lying below this plane and in the vertical middle plane of the vat, two lower longitudinal shafts arranged in the lower part of the vat, film supporting rollers on said upper and lower shafts, the film supporting rollers being placed end to end upon the respective shafts, a forth upper longitudinal shaft above the said horizontal plane and in the said vertical middle plane of the vat and means on the latter shaft for guiding and feeding the film into and out of the vat.

3. A machine for treating cinematograph films comprising a treating vat, parallel upper shafts arranged in the upper part of said vat, in the longitudinal direction of the same, lower longitudinal shafts arranged in the lower part of the vat, film supporting rollers placed end to end upon said shafts means for feeding the film through the vat and around the rollers, a frame in which the said upper shafts are rotatably supported at their ends, two parallel transverse supporting rods in which the lower shafts are rotatably supported at their ends and vertical suspending rods carrying said supporting rods and guided in said frame.

4. A machine for treating cinematograph films comprising a treating vat, parallel upper shafts arranged in the upper part of said vat, in the longitudinal direction of the same, lower longitudinal shafts arranged in the lower part of the vat, film supporting rollers placed end to end upon said shafts, means for feeding the film through the vat and around the rollers, a frame in which the said upper shafts are rotatably supported at their ends, two parallel transverse supporting rods in which the lower shafts are rotatably supported at their ends, vertical suspending rods carrying said supporting rods and guided in said frame and means for securing one of said suspending rods in vertically adjustable positions to said frame.

5. A machine for treating cinematograph films comprising a treating vat, parallel upper shafts arranged in the upper part of

said vat, in the longitudinal direction of the same, lower longitudinal shafts arranged in the lower part of the vat, film supporting rollers placed end to end upon said 5 shafts, means for feeding the film through the vat and around the rollers, a frame in which the said upper shafts are rotatably supported at their ends, two parallel transverse supporting rods in which the lower 10 shafts are rotatably supported at their ends, vertical suspending rods carrying said supporting rods and guided in said frame, means for securing one of said suspending rods in vertically adjustable positions in 15 said frame and an electric contact member on the other suspending rod for giving a signal in the case of breakage of the film.

6. A machine for treating cinematograph films comprising a treating vat, parallel upper shafts arranged in the upper part of 20 said vat, in the longitudinal direction of the same, lower longitudinal shafts parallel to the above shafts and arranged in the lower part of the vat, film supporting rollers placed end to end upon said shafts, means 25 for feeding the film through the vat and around the said rollers, a sheet metal cover for the vat, and means for suspending the said shafts from said cover, whereby they may be removed out of the vat together 30 with the cover.

In testimony whereof I have signed my name to this specification.

GEORGES AUGUSTIN SALINS.
